UNITED STATES PATENT OFFICE.

WILLIAM C. DEISS, OF BROOKLYN, NEW YORK, ASSIGNOR TO THE WHITE TAR COMPANY OF NEW JERSEY, INC., OF KEARNY, NEW JERSEY, A CORPORATION OF NEW JERSEY.

MANUFACTURE OF SIDE-OPENING GARMENT BAGS.

Application filed November 17, 1925. Serial No. 69,615.

This invention relates to the manufacture of side-opening garment bags and provides an economical method of producing such bags.

5 A primary object of the invention is to provide a process of manufacture that can be carried on continuously by automatic machinery.

In the drawings accompanying and forming a part of this specification, I have illustrated the invention embodied in a practical commercial form, but wish it understood that the structure may be modified in various ways without departure from the true spirit and scope of the invention as hereinafter defined and claimed.

In the drawings:

Fig. 1 is a diagrammatic view showing the relation of the steps in the process.

20 Fig. 2 is a detailed sectional view showing the method of forming the side tuck.

Fig. 3 is a detailed sectional view showing the location of the slitting knife.

Fig. 4 is a cross section on line 4-4 of 25 Fig. 1, showing on an exaggerated scale the strips of glue.

Fig. 5 is a cross section showing the shape of the paper roll after passing over the forming blades.

30 Fig. 6 is a view similar to Fig. 5 taken after the paper has passed the slitting knife.

Fig. 7 is a view similar to Fig. 5 taken after the paper has passed the pressing rolls.

35 Fig. 8 is a view similar to Fig. 5 showing the cross section of the completed bag.

Referring more particularly to the drawings, the paper is unwound from roll 5 and 40 passed over guide roll 6 and gluing rolls 7.

45 The gluing rolls are narrow and place continuous strips of glue or other adhesive on the bottom side of the paper. The paper is next passed over the reversing roll 8, whereby the lower surface carrying the strips of glue is brought to the top. Fig. 4 shows the relative position of the strips of glue at 9, 10 and 11.

50 The paper now passes over the forming blades, by which the paper is doubled over upon itself, and a tuck formed in each side as shown in Fig. 5. Two of the stationary blades are shown at 12 and 13, while 14 is an adjustable blade for forming a tuck of any desired depth. The blades 12 and 13

are recessed at 15 to avoid contact with the strips of glue 10 and 11, and the blades are so positioned as to hold the strip of glue 9 out of contact with the underlying fold.

55 A rotary cutting knife 16 is positioned near the end of the forming blades so as to slit the paper at the bottom of the right-hand tuck, leaving the paper in the condition shown in Fig. 6.

The paper now passes from the forming blades and through the driven rollers 17 and 18, which act as pulling rollers to unroll the paper from the roll 5 and carry it through the operations above referred to. At the same time rollers 17 and 18 act as 60 pressing rollers to press the glue strips 70 against the folds of the paper lying opposite them, as shown in Fig. 7.

As the result of this process there is formed a continuous tube having a tuck in the left side, and a slotted opening defined 75 by doubled edges at the right side, as shown in Fig. 8.

This tube now passes through a cutter composed of a stationary blade 19 and a rotating shear blade 20. Blade 20 can be rotated at any desired speed, thereby cutting the tube into lengths suitable for garment bags.

It will be obvious that the top and bottom of the blank can be closed by any well-known means, thereby producing a side-opening garment bag having double, reinforced edges along the opening.

It will be seen that the method of manufacturing bags above disclosed provides a 90 continuous process, since all of the operations are performed while the paper is in motion.

I claim:

1. In the process of producing bags, the steps of applying adhesive to certain parts of a strip of paper, forming the strip into a tube open at one side, and pressing the portions carrying adhesive against the portions lying opposite them.

2. In the process of producing bags, the steps of applying glue to certain parts of a strip of paper, folding the paper into tubular shape, slitting one side of the tube, and pressing the glued portions against the portions lying opposite them.

3. In the process of producing bags, the steps of applying glue to certain parts of a

strip of paper, folding the paper into tubular shape with a tuck in one side, slitting the paper at the bottom of the tuck, and pressing the glued portions against the portions lying opposite them.

4. In the process of producing bags, the steps of applying strips of glue to a sheet of paper, the first strip along one edge of the sheet and two other strips spaced from the edges of the sheet, folding the sheet into tubular shape with a tuck in one side, the first strip of glue overlying the unglued edge of the sheet and the other strips of glue lying opposite the folds of the tuck, slitting the paper within the tuck, and pressing the glued portions against the portions lying opposite them.

5. The method of producing bags which comprises applying glue to certain parts of a strip of paper, folding the paper into tubular shape, slitting one side of the tube, pressing the glued portions against the portions lying opposite them to form an open-sided tube, cutting the tube into bag lengths and closing the top and bottom of the blank.

6. The method of producing bags which comprises applying glue to certain parts of a strip of paper, folding the paper into tubular shape with a tuck in one side, slitting the paper at the bottom of the tuck, pressing the glued portions against the portions lying opposite them to form an open-sided tube, cutting the tube into bag lengths and closing the top and bottom of the blank. 20

7. The method of producing bags which comprises applying strips of glue to a sheet of paper, the first strip along one edge of the sheet and two other strips spaced from the edges, folding the sheet into tubular shape with a tuck in one side, the first strip of glue overlying the unglued edge of the sheet and the other strips of glue lying opposite the folds of the tuck, slitting the paper within the tuck, pressing the glued portions against the portions lying opposite them to form an open-sided tube, cutting the tube into bag lengths and closing the top and bottom of the blank. 35 40 45

In testimony whereof I affix my signature.
WILLIAM C. DEISS.
